Primary Examiner — Omeed Agilee(74) *Attorney, Agent, or Firm* — Jason R. Jones(57) **CLAIM**

The ornamental design for a surgeon support, as shown and described.

DESCRIPTION

FIG. 1 is a perspective view of a surgeon support in accordance with our invention;

FIG. 2 is a top view thereof, a bottom view being a mirror image thereof;

FIG. 3 is a side view thereof, an opposing side view being a mirror image thereof;

FIG. 4 is a front view thereof; and,

FIG. 5 is a rear view thereof.

The dot-dash lines in the drawing depict symbolic break lines. The break lines and any appearance of features between the break lines form no part of the claimed design.
